UNITED STATES PATENT OFFICE.

GEORGE H. HARDMAN, OF FALL RIVER, MASSACHUSETTS.

ROTARY ENGINE.

1,280,022.

Specification of Letters Patent. Patented Sept. 24, 1918.

Application filed January 16, 1917. Serial No. 142,601.

To all whom it may concern:

Be it known that I, GEORGE H. HARDMAN, a citizen of the United States, residing at Fall River, in the county of Bristol and State of Massachusetts, have invented certain new and useful Improvements in Rotary Engines, of which the following is a specification.

My invention relates to rotary engines operated by steam, compressed air, gas, or any other similar motive force.

The essential objects of my invention are to secure a maximum of leverage and to completely utilize the expansion of the energy employed. Further objects are to reduce the number and simplify the number of parts of the engine, to reduce the cost of manufacture of the same in a construction adapted for use under various conditions, and to insure a perfect and instantaneous co-operation of the cylinder and movable cylinder head.

To the above ends primarily my invention consists in such parts and combinations of parts as fall within the scope of the appended claims.

In the accompanying drawings which form a part of this specification, and which illustrate the principle of this invention in the best mode now known to me of applying that principle,

Figures 1 and 2 are front and end elevations respectively of a rotary engine, in this instance an air operated engine, embodying my invention,

Fig. 3, a longitudinal section of the same on line 3—3 of Fig. 2,

Figs. 4, 5, 6, and 7, transverse sections of the same on lines 4—4, 5—5, 6—6, and 7—7, respectively of Fig. 3,

Fig. 8, a section on line 4—4 of Fig. 3 showing the position of the parts when the cam has moved ninety degrees from its position in Fig. 4,

Fig. 9, a detail view of a cylinder head,

Fig. 10, a side elevation partially in longitudinal section of a modification of my engine in multiple or duplicate form, and

Fig. 11, a section of another modified form.

Like reference characters indicate like parts throughout the views.

The framework of my engine may be of any form of construction suitable for carrying the several details of mechanism. In the form thereof herein shown, it consists of a base 12 carrying uprights 13 supporting bearings 14 for the shaft 15. Upon the base

intermediate the uprights is a cylindrical standard or block 17 having a cylindrical end extension or hub portion or boss 18 of reduced diameter, forming a resultant annular end face 19 upon the standard. In the latter, adjacent said face is a substantially annular passage 20, from which leads a supply pipe 21 to admit, from any convenient source, the actuating power; in this instance compressed air. Adjacent the passage 20 is an annular passage 22 from which extends a pipe or opening 23 in the standard to the atmosphere. Communicating with the passage 20 in the face 19 of the standard are one or more, in this instance two, arcuate comparatively long slots or openings 25 which constitute energy ports for the admission of the expansive agent. These ports are located diametrically opposite each other. Openings or exhaust ports 27 in the face 19, of less dimensions than the ports 25, communicate with the passage 22, and are diametrically opposite each other alternating with the ports 25. The boss has a concentric cavity 29, and the standard has a concentric opening 30 to permit the loose passage of the shaft 15 therethrough. Fast to the latter within the cavity is a cam 32 having shoulders 33 equal in number to the cylinder heads.

In the construction illustrated, there are two cylinder heads 35, each comprising a body or plate 36 and a lateral cam projection 37, triangular in shape and provided with an inclined operating face 38. The cam is located midway the breadth of one of the broad faces of the body at its outer end, as shown in Fig. 9. The heads 36 are slidably mounted in slots 40 in the hub, and the cam projections slide in rectangular slots 41 opening into the first slots at right angles thereto, and extending to the periphery of the boss. The heads are in the path of the cam shoulders 33 and are successively elevated thereby to radially move the cam face 38 beyond the periphery of the boss 18.

Fast to the shaft 15 is a disk 43 having a peripheral rim 44 upon whose inner end is an inturned annular flange 45 slidable on the face 19 of the standard and provided with ports or openings 47 diametrically opposite each other adapted to register with the ports 25 and 27 when the disk rotates. The edge of the flange 45 slidably embraces the boss 18. An annular expansion chamber 46 is formed by the rim or flange, divided by

one or more transverse walls, or pistons 49 on the rim adjacent the openings 47, and in slidable contact with the periphery of the boss 18, into arcuate expansion chambers 50 5 revolvable with the disk relatively to the block; and each chamber has an opening 47. Upon one side of each piston 49 is an inclined cam face 52, and the opposite side of the partition has a slightly inclined cam face 10 53. Both cam faces are in annular alignment with the cam faces 38 when the cylinder heads are distended. The disk 43, rim 44, and flange 45 constitute a revolving cylinder. The operation of my engine is as follows, 15 reference being first had to Fig. 4. The compressed air or other energizing agent enters the passage 20 through the pipe 21, and enters a chamber 50 through a port 25 and an opening 47. Expansion of the agent 20 takes place in this chamber acting against a wall or piston 49 and an extended cylinder head 36. Since the latter is relatively stationary or non rotary, the piston 49 responds to the force and rotates the disk 43 and its 25 shaft 15 in the direction of the arrow in Fig. 4. It will be understood that during the expansive action of the active agent, the member 36 has been raised or extended by a cam shoulder 33 across one of the semi- 30 annular chambers 50 into contact with the flange 44 and forms an abutment or resisting area to the fluid agent under expansion. The elevation of the abutment member simultaneously raises the cam 37 above the 35 periphery of the boss. As expansion and rotation continue, the next successive piston 49 approaches the extended cylinder head, and the cam face 52 contacts with the cam face 38 whereby the member 36 is depressed 40 to the position shown in Fig. 8 with its outer extremity flush with the periphery of the boss 18 so as to permit the wall 49 to pass unimpeded. The cam 37 insures a quick and steady descent of the member 36, and as the 45 face 38 is inclined at the same degree as the face 52, there is no friction or wear of the parts. As the member 49 leaves the member 36, the latter in its expansive movement follows the cam face 53 thus insuring a more 50 perfect closure of the peripheral chambers at this instant than would otherwise result. During the described rotation, the openings 47 are simultaneously admitting the active agent through the ports 25 for a prolonged 55 period, since the ports 25 are more than half the length of one of the semi-annular cham-

bers, and next are registering briefly with the exhaust ports 27.

It will be understood that the member or radially movable abutments and axially 60 movable walls may be one or more, the number of ports being made to correspond with the number of annular chambers.

Any desired convenient resilient or mechanical means other than the cam 32 may 65 be employed for distending the cylinder heads.

The engine may be arranged in multiple if preferred, that is, any number of rotary disks and attached parts may be used. When 70 the engine is constructed in duplicate, the arrangement may be as shown in Fig. 10, wherein the boss is duplicated on the opposite end of the standard, and all the rotary parts moving in conjunction therewith are 75 similar to those already described. The passages 20 and 22, however, are preferably broadened into passages 55 and 56, and the cylinder heads are positioned at a radial angle differing from the angle of heads 36. 80

In Fig. 11 is shown the form of my engine wherein only one expansion chamber is used.

I claim:—

1. In a rotary engine, the combination of 85 a boss, a depressible radial head slidably mounted in the boss, a cam on the head, a rotary cylinder journaled on the head, and means on the cylinder slidably engaging the cam for depressing the head. 90

2. In a rotary engine, the combination with the boss, of a rotary cylinder journaled on the boss, a piston fast to the cylinder, a radially movable head in the boss, and a cam on the head actuated by the piston. 95

3. In a rotary engine, the combination of a stationary boss provided with a slot, a revolving cylinder comprising an annular chamber surrounding the boss, a piston transversely fixed in the cylinder across the 100 chamber, a cam face upon one side of the piston, a cam face disposed at a less angle upon the other side of the piston, and a depressible cylinder head mounted in the slot normally traversing the chamber in the path 105 of the cam face.

In testimony whereof I have affixed my signature in presence of two witnesses.

GEORGE H. HARDMAN.
